COUNTERDRIVE FOR DUAL PROPELLERS

Ralph C. Cavallaro, Branford, Conn.

Application April 30, 1943, Serial No. 485,250

1 Claim. (Cl. 170—135.5)

My invention relates to improvements in drives for propellers for aeroplanes and the like, the primary object in view being to provide a counter-drive for dual propellers, whereby both may be driven in unison at a high rate of speed around a common drive shaft in reverse directions, relatively, and at the same speed ratio, and which reduces torque to a minimum in high powered motors, is simple in construction, involves a minimum number of parts easy to assemble and disassemble, and is highly efficient in operation.

To the accomplishment of the above, and subordinate objects presently appearing, the preferred embodiment of my invention has been illustrated in the accompanying drawings set forth in detail in the succeeding description and defined in the claim appended hereto.

In said drawings:

Figure 1 is a view partly in longitudinal section and partly in side elevation illustrating the preferred embodiment of my invention, and

Figure 2 is a view in vertical transverse section taken on the line 2—2 of Figure 1.

Reference being had to the drawings by numerals, according to my invention, as illustrated, the drive, or power shaft 1 of the motor is extended out of a stepped down bearing sleeve 2 formed on the motor block 3, the sleeve comprising an annular, transversely flat seat 4 contiguous to block 3. The usual propeller 5 is keyed, as at 6, on the outer end of said shaft 1 and secured thereon by the usual cap plate 7 threaded onto said shaft and bolted, as at 8, to the hub of the propeller 5. In the rear of the first propeller 5 is a second propeller 9 freely rotatable about the shaft 1 and operative through drive mechanism now to be described.

Surrounding the shaft 1, between the second propeller 9 and the block 3, and rotatably concentrically about the shaft 1 is a gear housing 10 comprising a rear, dished, annular plate 11 and a front, hollow, dome-like, housing section 12 having an open rear side bolted to the rear plate 11, as at 13, and a front opening 14 cut of which the shaft 1 extends.

The housing 10 is rotatably mounted as follows. The rear plate 11 surrounds the sleeve 2 adjacent to seat 4, with a slight clearance and is provided on the rear face thereof with an annular, lateral flange 15 surrounding said seat 4. The flange 15 is fitted over a ball bearing unit 16 interposed between the same and the seat 4. A ball bearing unit 17 is countersunk in the inner face of the housing section 12 and fitted around

the shaft 1. The second propeller 9 is bolted, as at 18, to the front face of the housing section 12.

A pair of annular driving and driven, beveled gears 19, 20, respectively, are provided in the housing 10 in laterally spaced, opposed relation, the driving gear 19 being keyed to the shaft 1, as at 21, and the driven gear 20 surrounding the sleeve 2 and being bolted, as at 22, to the plate 11.

A plurality of motion transmitting, beveled gear pinions 23, relatively smaller than the driving and driven gears 19, 20, are interposed between the latter and preferably arranged 90 degrees apart as shown in Figure 2. The gear pinions are mounted on the outer end of the bearing sleeve 2 by means of an annular cap plate 24 fitting over said sleeve around shaft 1, an annular keeper plate 25 surrounding the shaft 1 and opposed to the plate 24, bolts 26 extending through said plates into the sleeve 2, and radial flanged studs 27 extending from the edge of the cap plate 24 and into axial sockets 28 in the inner faces of the gear pinions 23. The gear pinions 23 are provided on the outer faces thereof with stepped studs 29 each extended through a pair of inner and outer end thrust, roller bearing units 30, 31, clamped between a pair of gear housing rings 32, 33, opposed side by side in surrounding relation to the gears 19, 20, and said pinions 23 and having the inner side faces thereof socketed as at 34 to accommodate said bearing units 30, 31. The rings 32, 33, are suspended on the studs 29 by the bearing units 30, 31 and in the housing 10 as will be clear and are bolted together as at 35.

The operation of the described drive will be in part clear from the description of parts. Suffice it to explain, that as the shaft 1 rotates and correspondingly rotates the first propeller 5, the driving gear 19 is rotated thereby and drives the driven gear 20 through the medium of the gear pinions 23 in a reverse direction relative to the direction of rotation of said gear 19 and at the same speed ratio, the driven gear 20 rotates the housing 10 and the latter the second propeller 9 reversely relative to the direction of the rotation of the first propeller 5.

The foregoing will, it is believed, suffice to impart a clear understanding of my invention without further explanation.

Manifestly, the invention, as described, is susceptible of modification without departing from the inventive concept and right is herein reserved to such modifications as fall within the scope of the appended claim.

What I claim is:

The combination with the drive shaft of an engine and a propeller fast on said shaft, of a second propeller rotatable about said shaft and means to rotate said second propeller upon rotation of said shaft comprising a housing rotatable about said shaft and operatively connected to said second propeller, and reverse gearing in said housing operatively connecting said shaft to said housing, and comprising a pair of opposed annular beveled gears surrounding said shaft, beveled gear pinions interposed between said pair of gears and meshing therewith, and means to mount said

5 gear pinions for rotation about fixed axis, said means comprising a stationary unit fixed to said engine and including studs extending part way into said pinions on one side thereof, studs extending from the other sides of said pinions, end thrust bearings in which said last studs are mounted, and a pair of opposed rings surrounding said gears and pinions and clamping said end thrust bearings therebetween with the studs disposed radially of said rings.

RALPH C. CAVALLARO.
